UNITED STATES PATENT OFFICE.

WILLIAM DIETER, OF NEWARK, NEW JERSEY.

GEARING FOR TURBINE-DRIVEN TORPEDOES.

Application filed August 9, 1922. Serial No. 580,723.

To all whom it may concern:

Be it known that I, WILLIAM DIETER, a citizen of the United States of America, residing in Newark, in the county of Essex 5 and State of New Jersey, have invented certain new and useful Improvements in Gearings for Turbine-Driven Torpedoes, of which the following is a specification.

This invention relates to automobile torpedoes driven by turbine engines. As the turbine revolves at a speed much higher than the propellers, it is necessary to provide a train of gearing for reducing the turbine speed to that required for the propeller 10 shafts. In some instances the turbine wheels turn in opposite directions, as set forth in the patent to F. M. Leavitt, No. 1,088,080, dated February 24, 1914. In other cases the two turbine wheels are fixed on one shaft, 15 as set forth in patent to William Dieter, No. 1,407,262, February 21, 1922.

The present invention aims to adapt the mechanism for the transmission of a higher power, so as to increase the speed of the torpedo. It also provides an improved construction having certain other advantages, 20 as will be set forth.

The preferred embodiment of the invention is shown in the accompanying drawings, 25 wherein:

Figure 1 is a vertical longitudinal mid-section of the turbine wheels, nest of gearing, and supporting parts, to which the present invention relates.

Fig. 2 is a plan thereof partly broken away, and partly in section on line 2-2 in Fig. 1.

Fig. 3 is a vertical section on the line 3-3 in Fig. 2, looking from aft toward the bow 40 of the torpedo.

Fig. 4 is a rear elevation of the main frame alone.

Fig. 5 is a plan of the frame structure, the top frame being removed.

Fig. 6 is a fragmentary diagrammatic view corresponding to Fig. 2, showing a modified construction.

In the construction shown, the turbine wheels D D' are arranged to rotate in opposite directions, as in said Leavitt patent. The second stage wheel D is mounted on an inner shaft E, while the first stage wheel D' is mounted on a tubular shaft E'. On the shaft E is a pinion F, while on the shaft E' is a pinion F'. These pinions F F' correspond to the like-lettered pinions in said

Leavitt patent, which in that patent mesh with spur gears G G' respectively, which at their hubs are formed with bevel pinions H H' respectively. The pinions H H' mesh on the fore side with a bevel gear J, and on the aft side with a bevel gear J'. These bevel gears are fixed respectively on the inner propeller shaft C, and the outer tubular propeller shaft C', which extend aft and carry the respective oppositely-revolving propellers in the well known manner. According to the present construction, the same gears G G', pinions H H', and gears J J', are employed, with the same arrangement; 60 but instead of driving the gears G G' directly from the pinions F F', these respective gears and pinions are out of mesh, as shown in Fig. 2, and each pinion F or F' communicates motion to its corresponding gear through the interposition of two intermediate gears M M or M' M'. The arrangement is shown in Fig. 2 with respect to the pinion F', gears M' M', and gear G'. Precisely 65 the same arrangement is employed on the lower level with respect to the pinion F, gears M M, and gear G. The gears M M' are of a size intermediate the pinion and large gear, the proportions shown being 70 75 80 85 90 95 100 105 110

This arrangement of gearing enables twice the power at the same speed, or twice the torque at any speed, to be communicated from the turbine shafts to the gears G G', with the same strength of pinions and gears, that is, with teeth of a given size; this is because instead of the entire transmission from each pinion being at only one side, it occurs on two opposite sides, and the transmission to the gears G G' likewise occurs at two points instead of one. Thus, with the same factor of safety the gearing can transmit double the pressure, or, at a given speed, double the power. This has, in addition, the following important advantages:

1. Inasmuch as each pinion F and F' is transmitting equal and opposite rotative thrusts on diametrically opposite sides to the gears M M or M' M', it results that the reaction from the thrust on one side exactly equals that on the opposite side, and occurs in the contrary direction, so that instead of the driving torque resulting in crowding the shaft against one side of its bearings, the reactions are practically balanced, so that there is no effective tendency to crowd the axis of the shaft to either

side, and consequently any side thrust or reactive thrust of the turbine shafts in their bearings is reduced to negligible limits. It results from this that the frictional losses 5 heretofore encountered by reason of such reactive thrusts upon the turbine shaft or shafts are eliminated, with a corresponding saving in power.

2. The indirect transmission from the 10 small pinions F F' to the large gears G G' enables the transmission of power to be accomplished more advantageously. It is known to mechanics that the extreme practicable ratio in direct driving from a pinion 15 to a gear wheel is 1:5, beyond which there is introduced a wedging action between the gear teeth which would be impracticable for any serious power transmission, so that any higher ratio is never used where heavy 20 drives are required, and would be especially undesirable at high speed. In practice, the required ratio of reduction from turbine to propeller speeds makes it desirable in the proportioning of the train of gearing to 25 apply this extreme ratio of 5:1 as between the pinions and large gears. Nevertheless, this ratio involves an undesirable degree of wedging and rubbing action at the tooth faces, and at the higher speed which the 30 present invention aims to make practicable, that ratio would be even more undesirable. According to the present invention, by interposing the gears M M' it is possible, by making these gears of a suitable intermediate 35 number of teeth, to reduce the respective ratios to between 1:2 and 1:3. With these ratios it is possible to bring the coacting faces of the teeth into so close an approach to perpendicularity to the direction 40 of thrust as to communicate the motion with the greatest approach to a direct push, and with the least wedging and rubbing action. Accordingly, it results from the present invention that the transmission is at the gear 45 teeth comparatively frictionless, and there is also the further advantage that the operation is accompanied with substantial absence of vibration and greatly diminished noise.

50 The present invention further introduces improvements in the framing, whereby the bearings for the respective shafts and gears are supported.

The respective turbine shafts E E', which 55 are arranged to turn on a vertical axis, are mounted in bearings, preferably ball bearings, in top and bottom frames Q Q, and an intermediate frame P. The frame P is shown separately in Fig. 4, viewed from 60 the rear, and is shown in plan in Fig. 5 with the lower frame Q, the upper frame Q being removed. It is shown in Fig. 4 as of substantially H-shape, its middle cross bar supporting a boss P' which serves as a 65 thrust bearing for the inner propeller shaft

C, and having on its forward side a centering plug q; and being formed vertically with a central opening p for the passage of the turbine shafts, and for carrying the middle bearing thereof, as shown in section 70 in Fig. 1. The frame P is extended laterally to both sides, and is formed with vertically-extended flanges P'', whereby to distribute the thrust of the propellers over a large area of the transverse bulkhead K 75 of the torpedo. These lateral flanges extend outward into close relation with the shell or hull A of the torpedo, so that the propulsive thrust is not thrown primarily upon the middle of the bulkhead as heretofore, but is carried outward to the strong joint connection between the bulkhead and hull, whereby the thrust is communicated in substantially direct manner to the hull rather than the bulkhead, thereby contributing to 80 the strength of the torpedo, and especially enabling it to resist the greater strains to which a torpedo designed to run at higher speeds than those heretofore used will be subjected. The frame P may be fastened 85 to the bulkhead by bolts s s which may take into the joint between the bulkhead and hull, and also, if desired, by screws or bolts t which may engage the bulkhead. The top and bottom frames Q Q are fastened 90 at their bases against the top and bottom ends of the flanges P'', and are formed with openings coinciding with the opening p for the passage of the turbine shafts, and for receiving the top and bottom bearings i, j, 95 for these shafts, these bearings being shown as ball bearings, and the lower one, j, being shown as vertically adjustable, as heretofore. These bearings i j are thus housed in the frames Q Q instead of in a tubular 100 housing confined between these frames, as in the construction shown in my said Patent No. 1,407,262. The frames Q Q also provide bearings for the gear wheels M M'. As shown in Fig. 3, a fixed stud R extends 105 vertically between these frames and serves as the journal around which the gears M M' revolve. These gears are formed with tubular hubs of larger diameter, as shown at the right in Fig. 3, and anti-friction rollers 110 r r are arranged in the intervening annular space to form an anti-friction bearing for the respective gears. A crosshead S is connected by studs T T to the frame P. The middle part of this crosshead is formed 115 with an annular enlargement through which the propeller shafts pass, and which supports a bearing k (shown as a ball bearing) for the outer shaft C'. The vertical stud or fixed frame I, which affords the pivotal 120 bearing for the gears G G' and pinions H H', as heretofore, is supported at its ends by the frames Q Q. This shaft is laterally steadied by horizontal pins m, shown in 125 Figs. 1 and 2, fastened to its central hub and 130

having eyes which fit around the studs T T. The frames Q Q are of substantially A-shape and afford very rigid connections between the frame I and the main frame P, and between the frame I and the axial studs R R of the gears M M', so that the gears G G' and M M' are held in correct mesh. The studs R R are preferably constructed to pass at their middle portions through holes u u in the frame P, and are threaded at their ends to receive nuts x x by which they are firmly clamped to the frames Q Q. The whole structure is extremely rigid, while preserving the minimum of weight.

15 The shafts C C' are carried in bearings n and o, as heretofore, these being preferably ball bearings, as shown.

While the construction shown is believed to be the best embodiment of my invention, I do not desire to confine myself thereto, as the construction may be varied in many respects within the scope of the appended claims. For example, the intermediate gears M M' might be modified by forming each with two sets of teeth of different radius, as shown in Fig. 6, the teeth w of larger radius meshing with the teeth of the pinion F or F', while the teeth v of smaller radius mesh with the teeth of the gear G or G'. In this way part of the gearing down may occur between the pinion F or F', and the gear G or G'.

I claim as my invention:

1. In a turbine-driven torpedo having reducing gearing between the turbine and two oppositely-revolving propeller shafts comprising a pinion on a turbine shaft, a large gear wheel on an axis parallel with that of the turbine shaft driven therefrom and carrying a bevel pinion, and large bevel gears on the propeller shafts meshing with opposite sides of said bevel pinion, the combination therewith of two balanced intermediate gears meshing with said turbine shaft pinion on opposite sides, so as to balance the torque reaction thereon, and transmitting rotation to said large gear wheel at two points so as with given proportions to transmit a double thrust thereto with a given factor of safety, and of a size intermediate that of the pinion and large gear wheel.

2. In a turbine-driven torpedo having two oppositely-turning turbine wheels on shafts one within the other, and reducing gearing comprising a pinion on each turbine shaft, large gear wheels driven by the respective pinions, each carrying a bevel pinion, and large bevel gears on the propeller shafts meshing with opposite sides of said bevel pinions, the combination therewith of two balanced intermediate gears in the planes of the turbine pinion and large gear wheels meshing with each turbine shaft pinion on opposite sides, and transmitting rotation to

the appropriate large gear wheel at two points, so as with given proportions to transmit a double thrust thereto with a given factor of safety, and of a size intermediate that of the pinion and large gear wheel. 70

3. In a turbine-driven torpedo having reducing gearing between the turbine and propeller shafts comprising a pinion on a turbine shaft, a large gear wheel driven therefrom carrying a bevel pinion, and large bevel gears on the propeller shafts meshing with opposite sides of said bevel pinion, framing therefor comprising a main frame having a central bearing for a propeller shaft and extending outwardly adjacent the torpedo hull to transmit the driving thrust thereto, and top and bottom frames fixed to said main frame and affording supports for the bearings of the turbine shaft and gear wheels. 80

4. In a turbine-driven torpedo having reducing gearing between the turbine and propeller shafts comprising a pinion on a turbine shaft, a large gear wheel driven therefrom carrying a bevel pinion, and large bevel gears on the propeller shafts meshing with opposite sides of said bevel pinion, and framing therefor comprising a main frame having a central bearing for a propeller shaft and extending outwardly adjacent the torpedo hull to transmit the driving thrust thereto, top and bottom frames fixed to said main frame and affording supports for the bearings of the turbine shaft and gear wheels, and a crosshead 100 united to said main frame and having a propeller shaft bearing. 90

5. In a turbine-driven torpedo having reducing gearing between the turbine and propeller shafts comprising a pinion on a turbine shaft, a large gear wheel driven therefrom carrying a bevel pinion, and large bevel gears on the propeller shafts meshing with opposite sides of said bevel pinion, the combination therewith of two balanced intermediate gears meshing with said turbine shaft pinion on opposite sides, and framing therefor comprising a main frame, top and bottom frames fixed thereto, and studs passing through said intermediate gears and fastened at their ends to said top and bottom frames. 110

6. In a turbine-driven torpedo having reducing gearing between the turbine and propeller shafts comprising a pinion on a turbine shaft, a large gear wheel driven therefrom carrying a bevel pinion, and large bevel gears on the propeller shafts meshing with opposite sides of said bevel pinion, a transverse bulkhead, and framing comprising a main frame extending outwardly adjacent the torpedo hull and attached to said bulkhead, a cross-head united to said main frame, bearings for the respective propeller shafts in said main frame and crosshead, 120 125 130

and top and bottom frames fixed to said main frame and having bearings for said gear wheel and bevel pinion.

7. In a turbine-driven torpedo having reducing gearing between the turbine and propeller shafts comprising a pinion on a turbine shaft, a large gear wheel driven therefrom carrying a bevel pinion, and large bevel gears on the propeller shafts meshing with opposite sides of said bevel pinion, and framing comprising a main frame having a central thrust bearing for a propeller shaft, extending outwardly adjacent the torpedo hull to transmit thrust from the propeller shaft to the hull, and top and bottom frames carried by said main frame and having bearings for the turbine shaft and for said gear wheel and bevel pinion.

8. In a turbine-driven torpedo having reducing gearing between the turbine and propeller shafts comprising a pinion on a turbine shaft, a large gear wheel driven therefrom carrying a bevel pinion, and large bevel gears on the propeller shafts meshing with opposite sides of said bevel pinion, a transverse bulkhead, and framing comprising a main frame having at its middle a thrust bearing for a propeller shaft, extended thence diametrically of the torpedo, with means for attaching it to the torpedo hull for transmitting the propeller thrust thereto.

9. In a turbine-driven torpedo having reducing gearing between the turbine and propeller shafts comprising a pinion on the turbine shaft, a large gear wheel driven therefrom carrying a bevel pinion, and large

bevel gears on the propeller shafts meshing with opposite sides of said bevel pinion, a transverse bulkhead, and framing comprising a main frame having a center thrust bearing for a propeller shaft, extended diametrically of the torpedo and bearing against the torpedo hull for transmitting the propeller thrust thereto, and top and bottom frames fixed to said main frame and having bearings for said gear wheel and bevel pinion.

10. In a turbine-driven torpedo having reducing gearing between the turbine and propeller shafts comprising a pinion on a turbine shaft, a large gear wheel driven therefrom carrying a bevel pinion, and large bevel gears on the propeller shafts meshing with opposite sides of said bevel pinion, a transverse bulkhead, and framing comprising a main frame extending across the torpedo hull and attached to said bulkhead, having a central thrust bearing for a propeller shaft, and top and bottom frames fixed to said main frame and having bearings for the turbine shaft and gear wheels.

11. In a turbine-driven torpedo according to claim 1, the framing for the respective shafts and gearing comprising a main frame extending across the torpedo and having a central thrust bearing for a propeller shaft, and top and bottom frames fixed thereto, and bearing means for said intermediate gears carried between said top and bottom frames.

In witness whereof, I have hereunto signed my name.

WILLIAM DIETER.
